UNITED STATES PATENT OFFICE.

SAMUEL WILEY, OF THE UNITED STATES ARMY.

SIGNAL DEVICE.

1,329,736.

Specification of Letters Patent.

Patented Feb. 3, 1920.

Application filed October 19, 1918. Serial No. 258,850.

(FILED UNDER THE ACT OF MARCH 3, 1883, 22 STAT. L., 625.)

To all whom it may concern:

Be it known that I, SAMUEL WILEY, Captain, Ord., United States Army, a citizen of the United States, stationed at Washington, 5 District of Columbia, have invented an Improvement in Signal Devices, of which the following is a specification.

The invention described herein may be used by the Government, or any of its officers or employees in prosecution of work for the Government, or by any other person in the United States, without payment of any royalty thereon.

This invention relates to improvements in signals and like devices, and has for one of its objects to produce a device of this character having means whereby the charge firing pin, cap, or other like device is protected from injury or from premature firing during transportation, while at the same time the presence of the protecting element does not retard the operation of the firing pin when a sufficient impact is imparted to the protecting element.

Another object of the invention is to provide a device of this character having means for preventing the escape of sparks, flame or other products of combustion during the flight and thus preventing the course of the 25 signal or its source from being revealed.

With these and other objects in view the invention consists in certain new and useful constructions and combinations of parts as will hereinafter be more fully described and 30 pointed out in the claims.

Figure 1 is a side elevation of the improved signal device, partly in section.

Fig. 2 is a bottom plan view.

Fig. 3 is a bottom plan view with the 40 guard device removed.

Fig. 4 is a transverse section on the line IV—IV of Fig. 1 looking in the direction of the arrow.

Fig. 5 is a perspective view from beneath, 45 of the combined contents denoting and protecting cap.

The improved device comprises a charge inclosing shell 10 having a permanent closure 11 at one end, the shell being preferably of light sheet metal and the closure of wood. The opposite or charging end of the shell is adapted to receive a closure plug 12 of cork or similar compressible and expand-

sible material, to hold the charge within the shell.

The closure 11 is preferably formed with its upper portion reduced to enter the lower end of the shell and the lower portion extending beyond the side walls of the shell as shown in Fig. 1.

The closure 11 is provided with a central recess or chamber 13 and likewise provided with a combined base plate and firing pin support 14, the latter increased in thickness opposite the recess and arranged to support the fuse igniting pin or cap, indicated conventionally at 15. The thickened portion of the member 14 is formed with a cavity to receive the head of the pin or cap so that the latter is located above the outer line 60 of the member 14.

The fuse of the signaling charge is represented at 16, and terminates within the chamber 13 in proximity to the cap 15, so that when the latter is exploded it will 65 ignite the fuse and discharge the signal.

Bearing over the fuse igniting pin or cap supporting member 14 is a relatively thin protecting disk or plate 17, the members 14 and 17 being secured in place upon the closure member 11 by nails or other suitable 70 fastening devices 18.

By this arrangement the outer end of cap or fuse firing element 15 is spaced from the inner face of the protecting member 17 and 75 can be fired only by deflecting the portion of the member 17 which is located opposite the head of the cap, as shown in Fig. 1.

The fuse firing element is thus effectually 80 protected and guarded from contact with surrounding objects and will not therefore be prematurely "fired" during transportation or storage.

The member 17 is formed with an annular rib 19 pressed from the material of the member to reinforce and stiffen the protecting 85 plate and also to cause the portion of the plate externally of the rib to closely engage the member 14 and prevent the entrance of moisture.

The cavity 13 constitutes a gas chamber 90 permanently closed by the member 14, and into which the gas, sparks and other products of the combustion of the fuse 16 gather and are thus prevented from escaping during the flight of the signal. Thus the direc- 105

tion of the flight and the point from which the signal is fired will not be revealed to the "enemy". The "flight" of the signal will be effectually concealed and its presence revealed only when the explosion occurs.

5 The shell 10 is of sufficient length to permit the cork or plug 12 to be disposed below the outer line of the open or charging end, the projecting portion protecting the 10 plug from contact with surrounding objects, and also preventing injury to the charge in event of the shell being accidentally dropped with the charging end downward.

15 The member 20 which contains the designating configurations whereby the contents or nature of the contents of the signal is denoted, bears upon the cork 12 and is provided with projecting spurs or fingers 21 for insertion between the plug and the walls 20 of the shell, and the terminals of the fingers are bent beneath the inner face of the plug as shown at 22, to lock the member 20 in position and prevent its accidental displacement.

25 The outer end of the shell 10 projects to a sufficient distance beyond the plug 12 to fully protect the member 20 as well as the plug 12.

30 The shell 10, together with its attachments, is designed to be inclosed in a suitable holder, not shown, as it forms no part of the present invention, and adapted to be engaged over the muzzle of a shell projecting device such as a service rifle.

35 When the signal is to be fired the holder is attached to the projecting implement, for instance a service rifle, and the cartridge inserted in the rifle. The shell 10 is inserted in the holder and the cartridge fired in the 40 usual manner. The force of the discharge from the cartridge will be sufficient to throw the shell into the air the requisite distance and at the same time the force of the explosion will deflect the portion of the member 45 17 which extends over the outer head of the cap 15 against the cap and explode the latter which in turn ignites the fuse 16 and effects the firing of the signal, when the latter reaches a predetermined elevation.

50 The signal thus protected may be shipped and handled with safety and effectually protected from moisture, and the action of the elements, and will not reveal the line of flight when projected.

55 Having thus described the invention what is claimed as new is:

1. A projectile including a charge of combustible material and a fuse for igniting the charge, said projectile having a chamber in 60 which the outer end of the fuse terminates, a rigid protecting member bearing over the entire rear face of the projectile and forming a closure to the chamber, said protecting member having an outwardly opening 65 recess and an aperture providing communica-

cation between the recess and the chamber, a fuse igniting element supported in said aperture with its outer end within the outer lines of the protecting member, and a plate of compressible material extending over the 70 entire outer face of the supporting member and forming a closure to the recess and initially spaced from the igniting element.

2. A projectile including a charge of combustible material and having an outwardly 75 opening chamber, a rigid protecting member bearing over the entire rear face of the projectile and forming a closure to the chamber, said protecting member having an outwardly opening recess and an aperture 80 providing communication between the recess and chamber, a fuse igniting element supported in said aperture with its outer end within the outer lines of the protecting member, and a compressible member extending over the entire outer face of the protecting member 85 and forming a closure to the recess and initially spaced from the igniting element.

3. A projectile including a charge of combustible material and having a flat rear face and an outwardly opening chamber in said rear face, a rigid protecting member bearing over the entire rear face of the projectile and forming a closure to the chamber, said protecting 95 member having an outwardly opening recess and an aperture providing communication between the recess and chamber, a fuse igniting element supported in said aperture with its outer end enlarged and bearing within 100 the outer lines of the protecting member, and a compressible member extending over the entire outer face of the protecting member and forming a closure to the recess and initially spaced from the fuse igniting element.

4. A projectile including a charge of combustible material and a fuse for igniting the charge, said projectile having a chamber in which the outer end of the fuse terminates, 110 a rigid protecting member bearing over the entire rear face of the projectile and forming a closure to the chamber, said protecting member having an outwardly opening recess and an aperture providing communication 115 between the recess and the chamber, a fuse igniting element supported in said aperture with its outer end within the outer lines of the protecting member, a plate of compressible material extending over the entire 120 outer face of the supporting member and forming a closure to the recess and initially spaced from the igniting element, and fastening devices extending through the compressible plate, the protecting member and 125 into the body of the projectile.

5. A signal device including a charge holding shell, a plug of yieldable material inserted within the charge receiving end of the shell and spaced from the outer lines 130

of the same, and a member carrying the contents denoting configuration supported by the plug with its outer face within the lines of the adjacent end of the shell.

5 6. A projectile including a shell for containing a charge of combustible material, a base member secured to said shell having a chamber and an outwardly opening recess formed therein, a fuse extending through

the base member and terminating at one 10 end in said chamber, an apertured protecting member secured to said base, a primer supported in said apertured member and communicating with said recess and chamber, and a plate having a stiffening rib near 15 its outer edges but adapted to be distorted into said recess for firing the primer.

SAMUEL WILEY.
